UNITED STATES PATENT OFFICE.

ERRETT S. RHOADS, OF KANSAS CITY, MISSOURI

STORE-FRONT CONSTRUCTION.

No. 921,163.

Specification of Letters Patent. Patented May 11, 1909.
Application filed July 20, 1908. Serial No. 444,424

To all whom it may concern:

Be it known that I, ERRETT S. RHOADS, a citizen of the United States, residing at Kansas City, in the county of Jackson and State 5 of Missouri, have invented certain new and useful Improvements in Store-Front Construction, of which the following is a specification.

This invention relates to store front constructions and more especially to division or mullion bars therefor, and my object is to produce a division or mullion bar which can be easily and quickly secured in operative position and which possesses great strength and rigidity combined with simplicity and cheapness of construction, and which furthermore is of ornamental and attractive appearance.

To this end the invention consists in certain novel and peculiar features of construction and organization as hereinafter described and claimed; and in order that it may be fully understood reference is to be had to the accompanying drawing, in which—

25 Figure 1, is a sectional perspective view of a part of a store front embodying my invention. Fig. 2, is a vertical central section of the same. Fig. 3, is a perspective view of a part of the face-plate. Fig. 4, is a perspective view of a part of the outer clamp plate.

In the said drawing, 1 indicates a pair of window-lights between which projects inwardly the hollow rib or body of the outer clamping bar 2, said clamp bar consisting of 35 said hollow rib or body and laterally projecting wings 3 and being provided with a plurality of holes 4 in the bridge portion of the said body or rib.

5 indicates bolts projecting inwardly
40 through the holes 4 with their heads fitting
non-rotatably in the hollow or channel of the
body or rib.

6. indicates a face plate terminating at its side, margins in hooks 7, said face-plate being
45. arranged with its hooks embracing the wings of the clamping bar and its body portion covering the outer side of said clamping bar and bridging the hollow or channel therein so as to completely hide said bar from view.

50 A hollow stiffening bar 8 of suitable and by preference ornamental cross sectional form, is provided with shoulders 9 to bear against the inner faces of the window-lights and clamp the same firmly against the hooks 55 of the face plate as reinforced by the outer clamping bar, as said face-plate is preferably

of thin sheet metal and therefore incapable of alone holding the window-lights reliably against outward movement, and to guard against lateral movement of the stiffening bar its shoulders 9 are equipped with outwardly projecting flanges 10 engaging the adjacent vertical edges of the window-lights and interposed between the latter and the sides of the hollow body or rib of the outer clamping bar as shown clearly in Fig. 1. If desired the stiffening bar may be made in two similar sections, as shown, and if so said sections will preferably terminate their inner edges in parallel flanges 11 bearing against each other. The said flanges are provided because the stiffening bar is preferably made of thin metal and there would be a chance of their inner edges slipping past each other, when pressure was brought, as hereinbefore explained, to clamp them reliably together. The sides of the stiffening bar are provided with openings 12 to permit of the insertion of clamping nuts 13 at the rear ends of bolts 5 preliminary to securing said nuts upon the bolts, the first part of the operation being effected by hand, by preference, and the latter part by means of a suitable wrench, not shown, the sides of the stiffening bar being provided with vertical slots 14 which open into the openings 12 and are of sufficient length to enable the wrench, or equivalent tool to swing in a vertical plane and thus screw the nuts home upon the bolts until said nuts bear against the outer edges of the slots to effect the clamping of the window lights firmly between shoulders 9 and the reinforce hooks of the face plate. Where the stiffening bar is in two sections, as shown and hereinbefore referred to, they will preferably be clamped rigidly together by a suitable number of cross bolts 15 engaged by clamping nuts 16.

From the above description it will be apparent that I have produced a store front construction possessing the features of advantage enumerated as desirable and I wish it to be understood that I do not desire to be restricted to the exact details of construction shown and described as obvious modifications in the form, proportion, detail construction and arrangement of the parts will suggest themselves to one skilled in the art.

Having thus described the invention what I claim as new and desire to secure by Letters-Patent, is:—

1. A store front construction comprising a

pair of window-lights disposed with vertical edges adjacent and parallel, an outer clamping plate comprising a hollow body or rib projecting inwardly between the adjacent edges of said window-lights and laterally projecting wings overlapping the outer faces of said window-lights contiguous to said edges, bolts extending through the bridge portion or said body or rib with their heads fitting in the hollow or channel thereof, a face-plate attached to and covering said clamping bar and the heads of the bolts and bridging the hollow or channel of said clamping bar, a stiffening bar arranged inward of and bearing against the inner faces of the said window-lights at their adjacent edges and provided with vertical flanges interposed between the adjacent edges of the window-lights and the sides of the said body or rib, and clamping nuts engaging the inner ends of said bolts and engaging the stiffening bar to press the same outward against the window-light.

2. A store front construction, comprising a pair of window-lights disposed with vertical edges adjacent and parallel, an outer clamping plate comprising a hollow body or rib projecting inwardly between the adjacent edges of said window-lights and laterally projecting wings overlapping the outer faces of said window-lights contiguous to said edges, bolts extending through the bridge portion of said body or rib with their heads fitting in the hollow or channel thereof, a face-plate attached to and covering said clamping bar and the heads of the bolts and bridging the hollow or channel of said clamping bar, a stiffening bar arranged inward of and bearing against the inner faces of the said window-lights at their adjacent sides and provided with openings, and clamping nuts to be fitted in said openings and be screwed forward on said bolts.

3. A store front construction, comprising a pair of window-lights disposed with vertical edges adjacent and parallel, an outer clamping plate comprising a hollow body or rib projecting inwardly between the adjacent edges of said window-lights and laterally projecting wings overlapping the outer faces of said window-lights contiguous to said edges, bolts extending through the bridge portion of said body or rib with their heads fitting in the hollow or channel thereof, a face-plate attached to and covering said clamping bar and the heads of the bolts and bridging the hollow or channel of said clamping bar, a stiffening bar arranged inward of and bearing against the inner faces of the said window-lights at their adjacent edges and provided with openings and with vertical slots outward of and communicating with said openings and of greater length than the latter, and clamping nuts to be fitted into said open-

ings and to be screwed forward on said bolts until they engage the outer edges of the slots.

4. A store front construction, comprising a pair of window-lights disposed with vertical edges adjacent and parallel, an outer clamping plate comprising a hollow body or rib projecting inwardly between the adjacent edges of said window-lights and laterally projecting wings overlapping the outer faces of said window-lights contiguous to said edges, bolts extending through the bridge portion of said body or rib with their heads fitting in the hollow or channel thereof, a face-plate attached to and covering said clamping bar and the heads of the bolts and bridging the hollow or channel of said clamping bar, a stiffening bar arranged inward of and bearing against the inner faces of the said window-lights at their adjacent edges and provided with vertical flanges interposed between the adjacent edges of the window-lights and the sides of the said body or rib, said stiffening bar being also provided with openings in the horizontal planes of the bolts and nuts to be fitted into said openings and screwed home on said bolts until engaged with the stiffening bar to cause the same and the outer clamping plate to clamp the window-lights firmly in position.

5. A store-front construction, comprising a pair of window-lights disposed with vertical edges adjacent and parallel, an outer clamping plate, comprising a hollow body or rib projecting inwardly between the adjacent edges of said window-lights and laterally projecting wings overlapping the outer faces of said window-lights contiguous to said edges, bolts extending through the bridge portion of said body or rib with their heads fitting in the hollow or channel thereof, a face plate attached to and covering said clamping bar and the heads of the bolts and bridging the hollow or channel of said clamping bar, a hollow stiffening bar provided with outwardly disposed shoulders bearing against the inner faces of the window-lights and equipped with outwardly projecting flanges interposed between the adjacent edges of said window-lights and the said hollow body or rib, said hollow stiffening bar being provided with opposite openings in its sides in the horizontal plane of said bolts, and clamping nuts to be fitted in such openings and screwed home upon said bolts until they engage the sides of the clamping bar to cause the same to press the window-lights outwardly against the outer clamping bar.

6. A store front construction, comprising a pair of window lights disposed with vertical edges adjacent and parallel, an outer clamping plate comprising a hollow body or rib projecting inwardly between the adjacent edges of said window-lights and laterally projecting wings overlapping the outer faces of

said window-lights contiguous to said edges, bolts extending through the bridge portion of said body or rib with their heads fitting in the hollow or channel thereof, a face plate, 5 attached to and covering said clamping bar and the heads of the bolts and bridging the hollow or channel of said clamping bar, a stiffening bar 10 consisting of two sheet metal sections provided with engaging flanges at their inner edges and with shoulders at their front edges bearing against the inner faces of the window-lights and with flanges projecting outwardly 15 from the inner edges of said shoulders and interposed between the window-lights and the said hollow body or rib, the sides of said bar being provided with openings, clamping nuts to be fitted in said openings and screwed upon said bolts to simultaneously clamp the sections of the stiffening bar outwardly against the window-lights, and means for clamping said sections together. 20

7. A store front construction, comprising a pair of window-lights disposed with vertical edges adjacent and parallel, an outer clamping plate comprising a hollow body or rib projecting inwardly between the adjacent edges of said window lights and laterally projecting wings overlapping the outer faces of said window-lights contiguous to said edges, bolts 25 extending through the bridge portion of said body or rib with their heads fitting in the hollow or channel thereof, a face plate attached to and covering said clamping bar and the heads of the bolts and bridging the hollow or channel of said clamping bar, a stiffening bar 30 consisting of two sheet metal sections provided with engaging flanges at their inner edges and with shoulders at their front edges bearing against the inner faces of the window-lights and with flanges projecting outwardly 35 from the inner edges of said shoulders and interposed between the window-lights and the said hollow body or rib, the sides of said bar being provided with openings, clamping nuts to be fitted in said openings and screwed upon said bolts to simultaneously clamp the sections of the stiffening bar outwardly against the window-lights, bolts extending through the sides of said sections, and a clamping nut 40 engaging said bolt to clamp said sections 45 together.

In testimony whereof I affix my signature, in the presence of two witnesses.
